United States Patent [19]

Daniels

[11] Patent Number: Des. 335,652

[45] Date of Patent: ** May 18, 1993

[54] INTELLIGENT COMPUTER DISK ARRAY

[75] Inventor: George R. Daniels, Houston, Tex.

[73] Assignee: Compaq Computer Corporation, Houston, Tex.

[**] Term: 14 Years

[21] Appl. No.: 611,871

[22] Filed: Nov. 13, 1990

[52] U.S. Cl. D14/100; D14/109

[58] Field of Search D14/100, 102, 107, 109; D13/110, 160, 184, 199; 360/99.01-99.12; 361/390-395

[57] CLAIM

The ornamental design for an intelligent computer disk array expansion system, as shown and described.

DESCRIPTION

FIG. 1 is top, front, right side perspective view of an intelligent computer disk array expansion system showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a top, front, right side perspective view thereof with the retractable rear feet shown in their extended position;

FIG. 9 is a front elevational view thereof with the retractable rear feet shown in their extended position;

FIG. 10 is a rear elevational view thereof with the retractable rear feet shown in their extended position;

FIG. 11 is a top plan view thereof with the retractable rear feet shown in their extended position;

FIG. 12 is a bottom plan view thereof with the retractable rear feet shown in their extended position; and,

FIG. 13 is a front elevational view thereof showing the cover of the front panel removed and the retractable rear feet shown in a retracted position.
